UNITED STATES PATENT OFFICE.

VICTOR L. OESTNAES, OF WESTFIELD, NEW JERSEY, ASSIGNOR TO AMERICAN GASAC-CUMULATOR COMPANY, OF ELIZABETH, NEW JERSEY, A CORPORATION OF NEW JERSEY.

DESIGN FOR A REFLECTOR SIGNAL.

Application filed November 11, 1926. Serial No. 19,678. Term of patent 14 years.

To all whom it may concern:

Be it known that I, VICTOR L. OESTNAES, a citizen of the United States, residing in Westfield, county of Union, State of New Jersey, have invented a new, original, and ornamental Design for a Reflector Signal, of which the following is a specification, reference being had to the accompanying drawing, forming a part thereof.

In the drawing, Fig. 1 is a view in front

elevation of a reflector signal showing my new design and Fig. 2 is a view in side elevation thereof.

I claim:

The ornamental design for a reflector signal, as shown.

In testimony whereof I have hereunto signed my name this 8th day of November, A D., 1926.

VICTOR L. OESTNAES.
